(57) **CLAIM**

The ornamental design for a bottle, as shown and described.

DESCRIPTION

FIG. 1 is a top, rear, right side perspective view of the bottle; FIG. 2 is a right side elevational view thereof, the left side elevational view being a mirror image; FIG. 3 is a rear elevational view thereof; FIG. 4 is a front elevational view thereof; FIG. 5 is a top, plan view thereof; and, FIG. 6 is a bottom plan view thereof. The broken lines showing a cap in FIGS. 1-5 and the broken lines on the bottom surface in FIG. 6 are included for the purpose of illustrating environmental structure and form no part of the claimed design.
